UNITED STATES PATENT OFFICE.

WILLIAM F. SCHMIDT, OF GREEN BAY, WISCONSIN.

AUTOMATIC GREASE-PLUG LOCK.

1,399,085.

Specification of Letters Patent.

Patented Dec. 6, 1921.

Application filed March 19, 1920. Serial No. 367,261.

To all whom it may concern:

Be it known that I, WILLIAM F. SCHMIDT, a citizen of the United States, residing at Green Bay, in the county of Brown and 5 State of Wisconsin, have invented certain new and useful Improvements in Automatic Grease-Plug Locks, of which the following is a specification.

This invention relates to automatic grease 10 plug locks for grease cups of locomotive engines and other machines where the continual jar of the machinery tends to loosen the plug.

The object of the invention is to provide a 15 simple and efficient device for locking the plug against turning in one direction and permitting it to be turned in the opposite direction.

Another object is to provide such a device 20 with simple and efficient means for releasing the locking means when it is desired to remove the plug from the cup.

With the foregoing and other objects in view, which will appear as the description 25 proceeds, the invention resides in the combination and arrangement of parts and in the details of construction hereinafter described and claimed, it being understood that changes in the precise embodiment of the 30 invention herein disclosed may be made within the scope of what is claimed without departing from the spirit of the invention.

In the accompanying drawings:

Figure 1 represents a side elevation of a 35 grease cup embodying this invention with parts broken out and in section.

Fig. 2 is a similar view taken in a plane at right angles to Fig. 1.

Fig. 3 is a side elevation of the plug re- 40 moved from the cup; and

Fig. 4 is a horizontal section taken on the line 4—4 of Fig. 3.

In the embodiment illustrated a grease cup 1 is shown having laterally spaced apertured 45 projecting ears 2 on its outer face at its upper end for a purpose presently to be described. This cup 1 has an exteriorly threaded lower end 3 for insertion in the part of the machinery which it is designed to lubricate, a flange 4 projecting laterally from the cup above the threaded portion and operating as a stop for limiting the insertion of the cup.

Mounted to coöperate with the cup 1 is an 55 exteriorly threaded plug 5, it being under-

stood that the cup is internally threaded to receive this plug so that it may be screwed inward to force the grease out of the cup to the part to be lubricated. This plug 5 is provided at its upper end with a polygonal 60 head 6 which is adapted to be engaged by a wrench, or other suitable tool, for rotating the plug.

A recess 7 is formed in the outer face of the plug 5 and extends longitudinally there- 65 of, having the greater portion of its length terminating at its end at points spaced inwardly from the ends of the plug, as is shown clearly in Fig. 3.

The walls 8 and 9 of this recess 7 are 70 shown arranged at right angles to each other, the wall 8 being radially disposed relatively to the plug while the wall 9 is tangentially disposed, these walls being designed one to lock a pawl carried by the cup and the 75 other to permit said pawl to ride out of the recess in a manner presently to be described.

A locking pawl 10 is shown in the form of a substantially inverted T-shaped member, the shank 11 of which is pivotally mounted 80 at 12 between the ears 2 of the cup at a point near its free end, said free end being extended laterally inward toward the plug and provided at one side with a laterally projecting nose or finger 13 which is designed 85 to engage the radial wall 8 of the recess 7 for locking the plug against turning in the direction which would operate to unscrew it or separate it from the cup. The inturned laterally extending end 14 of the pawl has the 90 side thereof opposed to that which carries the nose 13 rounded so as to facilitate the passage of the wall 9 of the recess 7 from under said pawl when the plug is turned to screw it into the cup.

The head 15 of this T-shaped pawl has its arms 16 curved to conform to the shape of the cup 1 and these arms are weighted so as to hold the pawl in operative engagement with the plug, said head being spaced from 100 the cup a sufficient distance to permit it, when swung inwardly, to release the nose 13 of the pawl from the recess 7 of the plug and thus permit the plug to be removed when desired.

From the above description it will be obvious that the device constructed as shown and described will operate to hold the plug against turning in one direction and permit it to turn in the other direction, so that all 110

danger of its becoming unscrewed and detached incident to jar of the machinery may be prevented and that it may be readily turned for forcing out the grease without necessitating releasing of the pawl.

From the foregoing description taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention,

what I claim as new and desire to secure by Letters Patent, is:

A grease cup having a plug threaded therein, said plug having a ratchet groove therein, an inverted T shaped pawl having its shank pivoted on said cup and a nose extending laterally from its free end for engagement with said groove, the head of said pawl being spaced from the cup, and the arms of said head being extended laterally and curved around the cup to provide a weighted end for normally retaining said nose in engagement with said notch.

In testimony whereof I affix my signature in presence of two witnesses.

WILLIAM F. SCHMIDT.
